UNITED STATES PATENT OFFICE.

JOHN B. SMOUSE, OF CHICAGO, ILLINOIS, ASSIGNOR TO MORTON MANUFACTURING COMPANY, A CORPORATION OF ILLINOIS.

RELEASEABLE VESTIBULE-CURTAIN HANDLE.

Application filed March 14, 1927. Serial No. 175,094.

Considerable difficulties have been met with in using vestibule curtains between the vestibules of connected railway coaches, in that the handle is very often pulled off of the curtain or both the handle and curtain are pulled off of the curtain mounting due to the failure of the brakeman or other car attendant to unhook the curtain handle from its engagement with its retaining hook before a pair of coaches are separated.

This invention has been perfected for the purpose of obviating the above mentioned conditions by providing an improved vestibule curtain handle mechanism embodying a pivoted handle bar, the free end of which is suitably recessed or notched to permit the handle bar when in its lowered position for use to frictionally engage a spring latching member having a latching power sufficient to hold said handle bar in closed position under normal operating conditions but permitting automatic release of said handle bar when the same is subjected to abnormal strains as, for example, when two cars are separated and an attendant has neglected to release the vestibule curtain handle from engagement with a hook on an adjacent car.

It is an object of this invention to provide an improved releasable handle for a railway car vestibule curtain said handle being so constructed that under normal operating conditions it will remain latched while under abnormal conditions or strains the handle bar is adapted to be automatically released from a spring latching position before permitting injury thereto or to the vestibule curtain on which the handle is mounted.

It is a further object of this invention to provide a railway car vestibule curtain with an improved handle mechanism having a handle bar with one end pivotally supported on a spring support while the other end is notched to permit the same to lockingly engage a latch spring which under normal operating conditions is sufficient to hold the handle bar in a closed position but permitting release of said handle bar when the same has abnormal strains applied thereto.

Another object of this invention is to provide an improved handle mechanism adapted for use on vestibule curtains and the like, said handle mechanism embodying a sup-

port having recessed arms in one of which a spring support is mounted for pivotally supporting a notched handle bar while the other of said recessed arms is equipped with a spring latch adapted for holding the handle bar in a closed position under ordinary strains but permitting automatic release of said handle bar to obviate damage to the handle mechanism, when a handle bar is subjected to abnormal strains.

It is an important object of this invention to provide a handle mechanism of an improved simplified type adapted to be clamped or secured on a vestibule curtain or on any other selected device to permit the handle mechanism to be engaged on a vestibule curtain hook to hold the vestibule curtain stretched between two railway coaches under ordinary conditions, said handle mechanism having the handle bar thereof engaged on a resilient support and latched by a spring mechanism having a strength sufficient to hold the handle bar closed under ordinary conditions but permitting automatic release of the handle bar and disengagement from said hook when the handle bar is subjected to strains greater than the holding power of said latch spring.

Other and further important objects of this invention will be apparent from the disclosures in the drawings and specification.

The invention (in a preferred form) is illustrated in the drawings and hereinafter more fully described.

On the drawings:

Figure 1 is a front plan view of a releasable curtain handle mechanism in open position embodying the principles of this invention.

Figure 2 is an elevational view of the handle mechanism in closed position.

Figure 3 is a longitudinal section of the handle mechanism in open position.

Figure 4 is an end view of the handle mechanism taken on line 4-4 of Figure 3.

As shown on the drawings:

The releasable handle mechanism of this invention is primarily adaptable for use on the vestibule curtain of a railway car and comprises a support or base section embracing a connecting bar 1 having integrally formed on one end thereof a split clamping sleeve 2 having apertured clamping flanges

3 integrally formed on the split ends thereof. Also integrally formed on the clamping sleeve 2 is a hollow arm 4 having a passaged sleeve 5 forming a part thereof. The arm 4 is provided with a pocket or recess 6 open at its outer side and at the top. The sleeve 5 is provided with a transverse slot in which the lower end of a flat latch spring 7 is engaged. A rivet 8 or other suitable retaining member is engaged in the sleeve 5 for rigidly holding the lower end of the latch spring in position. The upper end of the latch spring 7 is bent at an angle to form a latch nose 9 while the upper end of said spring is bent downwardly to form a looped latch head 10.

Integrally formed on the opposite end of the connecting bar 1 is a second split clamping sleeve 11, the split ends of which terminate in integral apertured clamping flanges 12. Integrally formed on the clamping sleeve 11 opposite and parallel to the arm 4 is a hollow arm 13 provided with a chamber or recess 14 said chamber opening 25 through the inner side of said arm and through the top thereof. Integrally formed within the hollow arm 13 is a boss or block 15 suitably passaged to receive a rivet or retaining member 16 which is provided for the purpose of holding the lower end of a resilient mounting strap or plate spring 17 secured against the boss 15. The lower end of the mounting strap 17 seats in a notch 18 provided in one wall of the clamping sleeve 11 as clearly illustrated in Figure 3. The upper end of the resilient mounting strap 17 is curved or rolled to afford an integral bearing sleeve 19 in which a pivot pin or shank 20 is rotatably engaged. Secured on one 40 projecting end of the pivot pin 20 is the flattened end 21 of an arc shaped or curved handle bar 22. The free end of the handle bar 22 is tapered to form a tip 23 with one inclined face thereof provided with a latch notch at 24.

The improved handle mechanism, as hereinbefore stated, is adapted to be mounted on the free end of a railway car vestibule curtain to permit the curtain to be pulled or extended from one car across a vestibule passage so that the handle bar may be engaged on a retaining hook mounted on a vestibule face plate of an adjacent railway car. Under ordinary conditions the handle bar 22 is swung downwardly about its pivot pin 20 into the closed position shown in Figure 2 with the tapered end of the handle bar frictionally engaging the latch nose 9 formed on the upper end of the latch spring 7. The latch nose 9 is adapted to resiliently seat in the notch 24 in the end of the handle bar thereby holding the handle bar locked in a closed position ready for use under ordinary operating conditions. When the handle bar 22 is swung downwardly into the closed po-

sition shown in Figure 2, the spring support 17 is adapted to be slightly sprung upwardly as the tapered end of the handle bar is forced downwardly past the latch nose 9 until said latch nose is sprung into locking engagement in the notch 24.

In case the handle bar 22 is subjected to an abnormal tensional strain as, for example, when two railway cars are separated and an attendant has failed to unhook the curtain handle from its retaining hook, then said pivoted curtain handle bar 22 which has a sufficient strength to stand an additional strain permits the tapered latching end 23 of said handle bar to be pulled out of engagement with the resilient latch nose 9 of the latching spring 7 which is sprung outwardly by the abnormal pull on the handle bar 22 to permit automatic release of said handle bar and disengagement of said handle bar from the retaining hook mounted on one of the railway cars. When the handle bar is released by an abnormal strain both the resilient supporting spring 17 and the latch spring 7 are adapted to be sprung to permit release of the handle bar. The automatic releasing of the improved handle mechanism prevents the destruction thereof and obviates damage to the vestibule curtain on which the handle is mounted when the handle mechanism is subjected to excessive pulls or strains. The releasing feature of the handle mechanism thereby obviates the replacement of said handle mechanism, saving the expense of supplying a new handle which would be necessary if one of the old rigid type handle mechanisms were mounted on the vestibule curtain.

The improved handle mechanism of this invention having a resiliently supported handle bar adapted to be held in a releasable latched position by a spring latching member is adapted primarily for use on a railway car vestibule curtain. It will, however, be understood that the improved handle mechanism may also be used in combination with many other devices and in various locations in which a releasable handle bar of the type described will function to prevent damage to the handle mechanism and to the device on which it is mounted in case the handle mechanism is subjected to an abnormal strain.

I am aware that many changes may be made and numerous details of construction may be varied through a wide range without departing from the principles of this invention and I, therefore, do not purpose limiting the patent granted hereon, otherwise than necessitated by the prior art.

I claim as my invention:

1. The combination with a car vestibule curtain and a car vestibule curtain hook, of a handle base section secured to said curtain, a resilient support in said handle base sec-

- tion, a handle bar pivoted on said resilient support, and a spring latch in said handle base section adapted to be frictionally engaged on one end of said handle bar to hold the same latched in a closed position under normal operating conditions and releasable under abnormal operating conditions when said handle bar is subjected to abnormal tensile strains.
- 10 2. A vestibule curtain handle mechanism comprising a base section, means forming a part thereof for supporting the base section on a curtain, hollow arms formed on said base section, a resilient support in one of said arms, a handle bar pivotally mounted on said resilient support, and a spring latch in the other of said hollow arms adapted to frictionally engage said handle bar to hold the same latched in closed position.
- 15 3. A handle mechanism comprising a connecting bar, split clamping sleeves integrally formed on the ends thereof, a chambered arm integrally formed on one of said clamping sleeves, a resilient support mounted in said arm, a handle bar pivotally mounted on said resilient support with one end of said handle bar tapered and provided with a latch notch, a chambered arm formed on the other of said clamping sleeves, and a spring latch mounted therein adapted to lockingly seat in the latch notch of said handle bar to hold said handle bar in a closed position for use under normal operating conditions and permitting automatic release of said handle bar when the same is subjected to abnormal strains.
- 20 4. A handle mechanism comprising a base section, hollow arms integrally formed thereon, a resilient support in one of said arms, a notched handle bar pivotally mounted on said resilient support, and a spring latch in the other of said hollow arms adapted to hold said handle bar latched in closed position under normal strains and permitting said handle bar to swing outwardly into open position against the action of said spring latch when the handle bar is subjected to strains greater than the resistance of said spring latch.
- 25 5. A curtain handle of the class described comprising a base, supporting members formed on said base, a hollow arm formed on one end of said base, a boss formed in said hollow arm, a spring support in said hollow arm secured to said boss, a bearing sleeve formed on said spring support, a pin journaled in said sleeve, a handle bar secured on one end of said pin, said handle bar having the other end thereof tapered and notched, a second hollow arm formed on said base, a slotted sleeve formed in said second arm, a latch spring in said second arm having one end thereof secured in said slotted sleeve, and a latch head integrally formed on the other end of said latch spring
- 30 adapted to lockingly engage the notched tapered end of said handle bar to hold the same latched in closed position under ordinary strains and permitting release of said handle bar when the same is subjected to abnormal strains.
- 35 6. A handle mechanism comprising a base section, hollow arms integrally formed thereon, spring members supported in said hollow arms, and a handle bar pivotally mounted on one of said spring members and adapted to releasably engage the other of said spring members when in closed position.
- 40 7. A handle mechanism comprising a base, means for mounting the same, hollow arms on said base, plate springs in said hollow arms, a handle bar pivotally mounted on one of said springs, and a latch head integrally formed on the other of said springs adapted to lockingly engage the other end of said latch bar when in closed position permitting said latch bar to be released when subjected to a strain greater than the resisting power of said springs.
- 45 8. A handle mechanism comprising a pair of hollow arms, a spring mounted in one of said arms, a handle bar having one end thereof pivotally supported on said spring, and a latch spring in the other of said arms adapted to releasably engage the other end of said handle bar to hold the same locked in closed position and permitting release of said handle bar when an abnormal pull is applied thereto.
- 50 9. A handle mechanism comprising an arm, a mounting spring supported therein, a handle bar pivotally mounted on said mounting spring, a second arm and a spring latch in said second arm adapted to releasably engage said handle bar to hold the same locked in position under normal conditions and permitting release of the handle bar when an abnormal pull is applied thereto.
- 55 10. A handle mechanism comprising a base, a spring support mounted thereon, a latch spring also mounted on said base opposite said spring support, and a handle bar having one end thereof pivotally mounted on said spring support and the other end tapered and notched to permit the same to move the latch spring outwardly when the handle bar is moved into closed position to be held in said position by said latch spring.
- 60 11. A handle mechanism comprising a base, a pair of hollow arms integrally formed thereon, a spring support in one of said hollow arms, a latch spring in the other of said hollow arms, a latch nose formed on said latch spring, a handle bar, and a pin mounted in one end of said handle bar and rotatably engaged in said spring support, said handle bar having the opposite end thereof tapered with one of the tapered surfaces thereof having a locking notch therein
- 65 70 75 80 85 90 95 100 105 110 115 120 125 130

adapted to receive said latch nose when the handle bar is moved into closed position and the tapered end of said handle bar is forced past said latch nose.

5. 12. A handle mechanism comprising a base member, a mounting spring and a latch spring mounted thereon, and a handle bar

supported on said mounting spring adapted to be moved into and out of latching engagement with said latch spring.

10 In testimony whereof I have hereunto subscribed my name.

JOHN B. SMOUSE.
